Primary Examiner — Catherine A Tuttle(74) *Attorney, Agent, or Firm* — Baker and Rannells, PA(57) **CLAIM**

The ornamental design for a disc golf goal adapter, as shown and described.

DESCRIPTION

FIG. 1 is a top perspective view of the disc golf goal adapter showing my new design together with broken lines representing its environment;

FIG. 2 is a top perspective view similar to FIG. 1 but without the environmental structures;

FIG. 3 is a bottom perspective view thereof;

FIG. 4 is a front elevational view thereof, whereby the opposing rear elevation view is a mirror image;

FIG. 5 is a right side elevational view thereof, whereby the opposing left side elevation view is a mirror image;

FIG. 6 is a top plan view thereof; and,

FIG. 7 is a bottom plan view thereof.

The broken lines showing the environmental structure in FIG. 1 and portions of the disc golf goal adapter in FIGS. 1-3, 6 and 7 are for illustrative purposes only and form no part of the claimed design.
